UNITED STATES PATENT OFFICE.

JOHN T. RICHARDS, OF CHICAGO, ILLINOIS, ASSIGNOR TO THE CHICAGO COFFIN COMPANY, OF SAME PLACE.

COFFIN.

SPECIFICATION forming part of Letters Patent No. 333,255, dated December 29, 1885.

Application filed September 29, 1884. Serial No. 144,182. (No model.)

To all whom it may concern:

Be it known that I, JOHN T. RICHARDS, a citizen of the United States, residing at Chicago, county of Cook, and State of Illinois, 5 have invented certain new and useful Improvements in Coffins, of which I do declare the following to be a full, clear, and exact description, reference being had to the accompanying drawings, forming part of this specification.

Figure 1 is a view in vertical longitudinal section of a coffin embodying my invention. Fig. 2 is a plan view, and Fig. 3 is a plan view with portions removed and broken away 15 for better illustration of subjacent parts.

In the manufacture of the old style of coffins having inclined lids it has heretofore been proposed to form a lid of two separate sections, the forward section, or that above the 20 head and shoulders of the corpse, being removably held in place by means of dowels that entered the fixed section and catches that engaged with the sides of the coffin. This construction is objectionable, however, for the 25 reason that in moving the coffin the edges of the removable section of the lid which extend to the body of the coffin are liable to be struck and the dowels or catches to be loosened or displaced. In constructing burial 30 caskets, also, the lids, formed usually of one piece, have been provided with a removable panel having a rear beveled edge, which engaged with the correspondingly-beveled edge of the main portion of the lid, and having 35 around its upper edge a separate molding, which served to prevent the panel from dropping through the opening of the lid. This last construction, however, is not well suited to the manufacture of wooden coffins, particularly 40 where cheapness is a desideratum, since the raised lid, being of a single piece, would require to be made of very thick and expensive lumber, and the molding around the edge of the removable panel would increase the cost, 45 and unless carefully and securely joined would be liable to warp and loosen.

My present invention, which relates to the construction of the coffin-lid, has for its object to provide the lid at its forward portion with a 50 removable panel of such construction and attached to the lid in such improved manner

that a lid may be simply and cheaply made, through which ready access may be had to the corpse.

To this end my invention consists, primarily, 55 in forming the coffin-lid with a rim that extends around the entire body of the coffin, and that may be securely fastened in place, the raised portion or top panel of the lid being adapted to engage with the rear edge of a removable panel that is formed sufficiently broad to rest upon the rim and cover the opening 60 therein, and is provided with a catch at its front end to detachably attach it to the rim.

My invention further consists in forming a 65 joint between the raised portion of the lid and the removable panel of irregular beveled outline, so as to form a secure connection between the parts at a very slight expense in manufacture.

My invention also consists in providing the 70 coffin-lid with a name-plate panel that shall serve to hide in great measure the joint between the fixed and removable panels of the lid, which joint in case of shrinkage would otherwise mar the appearance of the coffin.

In the drawings, A designates the rim of my improved lid, which rim extends around the entire body of the coffin, and will be securely screwed to the edges thereof when 80 the corpse has been placed therein, or when the coffin is put together for transportation. Upon this rim is fixed the raised portion or top panel, B, which extends to about midway of the coffin, and has its front edge, 85 b, beveled and preferably of irregular outline, as shown. With the beveled front edge of the top panel engages the rear beveled edge of the removable panel C, which carries the glass C', that may be protected by the cover 90 D, and is provided at its front end with a suitable catch, C², that engages with the rim B of the lid. The panel C is formed enough broader than the opening of the rim to be supported by this rim without, however, extending to 95 its edge, where it would be liable to be struck and accidentally displaced. A name-plate panel, E, is fixed to the top panel, B, in such position that its front edge projects over the joint between the panels B and C, thus serving not only to hide in great measure this 100 joint, but also, in case of any shrinkage of the

panel and consequent loosening of the joint, to more securely hold the removable panel in place. When the name-plate panel is used, as shown, the abutting edges of the panels B and C may be made square, the removable panel being held in place by means of the name-plate panel and the catch C². The joint shown is, however, the preferred construction, as the beveled edges hold the parts together securely, and the irregular shape of these edges guards against any lateral movement of the removable panel. By extending the rim around the entire body of the coffin and forming the panels in the manner shown not only is cheapness of construction secured, but the rim serves also to firmly brace the body of the coffin, and thus lessen the danger of warping or of breakage in transportation. It is to be understood, of course, that variations in the details of construction may be made without departing from the spirit of my invention. Thus, for example, instead of the beveled joint between the panels, any equivalent form of joint may be substituted therefor.

Having thus described my invention, what I claim as new, and desire to secure by Letters Patent, is—

1. In a coffin, the combination, with the lid-
rim consisting of a simple wooden strip or
strips adapted to be secured to the edge of the 30
coffin, of a fixed panel broader than the opening
of said lid-rim and connected thereto, and a
movable panel broader than the opening of the
lid-rim and adapted to rest thereon, said fixed
and removable panels being connected to- 35
gether, as described, and said removable panel
being provided with a catch for engagement
with the lid-rim, substantially as described.

2. In a coffin, the combination of the main
lid-rim extending around the entire body of 40
the coffin, the raised top panel fixed to said
lid-rim and having a beveled front edge of
irregular shape, and the removable panel
formed broader than the opening of the lid-
rim and having its rear edge beveled and of 45
irregular shape to engage with the edge of the
raised panel and prevent lateral displace-
ment, and a suitable catch to fasten the re-
movable panel to the lid-rim, substantially as
described.

JOHN T. RICHARDS.
